ELIAS E. RIES, OF NEW YORK, N. Y.

TELEPHONE-EXCHANGE APPARATUS.

No. 796,089.

Specification of Letters Patent.

Patented Aug. 1, 1905.

Application filed May 20, 1904. Serial No. 208,894.

To all whom it may concern:

Be it known that I, ELIAS E. RIES, a citizen of the United States, and a resident of New York city, in the county of New York and State of New York, have invented certain new and useful Improvements in Telephone-Exchange Apparatus, of which the following is a specification.

My invention relates to telephone-exchange switch apparatus; and the object is to improve and facilitate the operation of a manual exchange more particularly with reference to the operation of clearing out.

Hitherto it has been the practice to provide in connection with the central-office apparatus a pair of clearing-out lamps or other devices, ordinarily termed "supervisory" lamps, one of which lights when one of two connected subscribers hangs up his telephone, while the other lights in response to the hanging up of the other subscriber's instrument upon the hook or other support provided. In connection with such supervisory lamps there has usually been associated a "pilot-lamp" for the purpose of more definitely calling the operator's attention to the signals indicated by the double supervisory or clearing-out lamps. In this system, in addition to the confusion arising from and notwithstanding the employment of so large a number of lamps, and especially owing to the negligence of subscribers in returning their apparatus to normal condition, it frequently becomes necessary for the central-office operator to "listen in" upon the conversation and frequently to make inquiries of one or the other subscriber in order to determine whether it is proper to disconnect the two subscribers. In other words, the supervisory part of the system fails of its intended object, and the giving of prompt, accurate, and efficient service is greatly interfered with.

The purpose of my present invention is to overcome this difficulty and at the same time to permit the operation to be carried on by the use of a single supervisory lamp or other indicator, as well as to greatly simplify the work of central operators and materially improve and expedite the giving and taking down of connections and eliminating other disadvantages incident to existing telephone switchboard practice.

Other objects of my invention are to simplify the work of the central operator by arranging the apparatus involved in the act of

signaling, (both at subscribers' stations and at the exchange,) so as to insure at all times and under all circumstances the prompt and necessary coöperation of the subscribers themselves, and to thereby reduce to a minimum or eliminate altogether the delays resulting under existing practice from error, carelessness, or neglect on the part of both the public and the switchboard-operator.

My invention consists in the combination, with a single supervisory lamp or clearing-out device for each cord-circuit, of means subject to the conjoint action of the connected subscribers' circuits for controlling the lighting or extinguishment of the lamp, as the case may be, and subscribers' apparatus, comprising automatic switching or circuit-changing devices of the gravity type, embodied in or constituting a part of the receiving instrument itself and so organized that when the instrument is laid aside after use the circuits will be automatically changed in the instrument and bring about the necessary changes of electrical condition to cause the single supervisory lamp to light or to be extinguished, as the case may be, at the central office when, and when only, both subscribers have finished their conversation.

While I use the term "supervisory lamp," I do not wish to be understood as restricting myself to the use of such an instrument as an indicator or clearing-out signal, since I may use in place thereof an electromagnetic drop or other signaling device.

My invention consists, further, in combining the supervisory lamp or other device with the repeating-coil of the cord-circuit by providing for said coil a suitable armature, which controls directly or indirectly the circuit of the supervisory device and which will respond and cause the supervisory device to indicate that the conversation is ended only when a similar electric condition exists in both sides of the coil.

My invention consists, furthermore, in the combination, with the novel switchboard signaling devices referred to, of apparatus at the subscribers' stations so constructed and arranged that the lifting of the telephone-receiver to the ear for conversation will automatically operate the calling-signal at central, and so that the removal of the receiver from the position which it occupies when held against the ear, whether it be placed upon a hook-support or not, will automatically operate the said signal or signals to indicate

(when such removal of the receiver from its listening or conversational position is effected by both of the connected subscribers) that the conversation is at an end and that the connection at central is to be taken down.

My invention consists in the novel combinations of devices hereinafter described and then specified in the claims.

In the accompanying drawings, Figure 1 is a diagram illustrating my invention by showing two subscribers connected by one cord-circuit, together with the devices and appurtenances in usual diagrammatic form. Fig. 2 is a diagram showing a modification in the manner of controlling the operation of the supervisory device. Fig. 3 is a modification in the line-signals shown in Fig. 1. Fig. 4 illustrates, partly in diagram, a subscriber's telephone equipment, showing the position of the receiver when not in use.

Referring to Fig. 1, the two sides of each subscriber's circuit are indicated by the numerals 5 14. At the central office the circuit of each subscriber may include, as indicated at the left of the diagram, the signal-receiving electromagnet 9 and the usual source of energy 8, said magnet being connected with the two sides of the circuit through a pair of contacts 6, insulated from one another and carried by the armature of a cut-off relay 52, connected on one side to ground 51 and on the other by wire 52^a with a sleeve-contact 19^b, which is engaged by the sleeve 19^a of the operator's plug 19^c, forming the terminal of the cord-circuit. When the two sides 5 14 of the circuit leading to the subscriber's station are connected there by the proper circuit-closing device, the magnet 9 by attracting its armature 10 closes the circuit 12 for a source of energy 11 through the line-lamp 13, thus calling the central operator. When the operator inserts the plug of a cord-circuit into the spring-jack, the circuit of a suitable source of energy 50^a is closed through the sleeve 19^a, sleeve-contact 19^b, and magnet 52, so as to break the line connection of magnet 9 at the back contacts of cut-out relay 52 and to thereby extinguish the lamp 13. At the same time the generator 50^a operates the relay-magnet 41 to draw up its armature, which is maintained in this condition while the plug 19^c remains in the jack. The two sides of the circuit 5 14 connect, as usual, to the jack-springs 16 and 17, as usual in the art, whence connection is formed, as usual, with the two sides 21 25 of the cord-circuit, which connects, respectively, through helices 22 and 24, forming one side of the repeating-coil with the source of central energy 23.

27 is the operator's ringing-key, which acts on springs 20 26 in the cord-circuit to connect them, respectively, with the poles of ringing-generator 28, as usual in the art.

The operator's head set, connected in wire 36 across the sides of the cord-circuit, is shown

as comprising the usual transmitter 37, receiver 38, and listening-key 51^a.

At the central office and in connection with each cord-circuit a clearing-out signal consisting of lamp 42 or other device is provided. This is in a local circuit with a generator 40. This local circuit includes the contacts of a relay electromagnet 41, which is in the circuit of battery 50^a and is energized through ring-contact 19^b and cut-off relay 52 when the plug 19^c is inserted in the jack. The connection of battery 40 is through the front contact of relay 41 and through the back contact 39 of an armature-lever 34, which is normally held down by the action of spring 35 or other means, but which under one method of operating my invention, hereinafter described, is elevated so as to break contact with 39 simultaneously with the closing of this local circuit by the armature of the relay 41, when the latter is energized by the insertion of the answering-plug into the jack of the calling subscriber. The armature-lever 34 is subject to the action of the two sets of helices 22 24, 22 24, wound upon the U-shaped core 22' of my repeating-coil, which helices are respectively in portions of the cord-circuit leading, respectively, to the two subscribers' stations, so that the armature 34 may not close the circuit of battery 40 unless the circuits of both subscribers are open. These helices or coils, as shown, comprise the ordinary windings of the repeating-coil itself, which is connected to the cord-circuit and generator 23, as already described and as usual in the art. Under these conditions and as illustrated in Fig. 1 of the drawings the armature 34 constitutes a part of the magnetic circuit for the repeating-coil, the arrangement being such, as will hereinafter more fully appear, that the magnetic circuit of the repeating-coil will be closed through its armature while conversation is going on.

The lamp or signal 42 may be used either as a combined supervisory and clearing-out signal or as a clearing-out signal alone, according to the adjustment of spring 35. In the former case the spring 35 should be given such a tension that the action of the coils in both subscribers' circuits will be required in order to open the circuit of battery 40. When the lamp 42 is used as a clearing-out signal alone, the spring 35 is given a lesser tension, so that the armature will be lifted by the action of the coil in one subscribers' circuit.

The preferred devices at subscriber's stations (shown at the left and right of Fig. 1) comprise the following: 15 is a metal cup mounted upon or within the receiver, the coils of which are indicated at 56. Within the cup, but out of contact with it, are mounted the contact-ring 55 and a central contact 54. Within the cup is also a body 2 of mobile matter like mercury, adapted to bridge the gap between the metal cup and ring 55 when

the parts are in the position shown in the drawings, which is that which they are supposed to occupy when the receiver is held to the ear. The coils 56 are, however, shown in the diagram in the position which they would occupy naturally when the receiver is at rest or hanging by its cord, as indicated in Fig. 4. In this position the cup and associated parts 54 and 55 would be turned through an angle of ninety degrees from that shown, and the mercury would occupy the space at the apex of the cup, but out of contact with 54. In case a return-signal is desired a visible or audible signal device or telltale 53 may be provided, which is operated from battery 8 at the exchange as the mercury 2 momentarily connects cup 15 and contact 54 in its passage from normal to listening position. In passing from listening to normal position the mercury again makes momentary connection, and the signal 53 is operated from battery 23 or other source connected across the two sides of the subscriber's circuit at central. This signal informs the subscriber that the line from this station to central is in proper working condition and that his signal has been received, and thus acts as a check upon the central operator and also permits him in case of failure to report the line out of order over some other telephone, thereby avoiding the loss of time that would otherwise be incurred in frequent attempts to signal central in the event that his line is not in proper condition. It also warns the subscriber, should he allow his receiver to wander from his ear while he is "holding the wire," and compels him or his correspondent to remain at "attention" during the time the line is at their joint disposal. This device I term a "telltale-signal."

4 is the usual transmitter at the subscriber's station, 32 the bridging-bell, and 33 the condenser in the bridge. As illustrated in Fig. 1, the parts are shown as being in condition for conversation. When the signal 42 is employed as a combined supervisory and clearing-out signal, the operation of the devices is as follows: When the subscriber at the left lifts his receiver to the ear, the mercury 2 after passing by contact 54 and operating signal 53, as already described, continues this movement until it closes the circuit between the mercury-cup 1, which is in connection with the line 14, and the talking-ring 55, which is in electrical connection through the receiver-coil 56 and transmitter 4 to one wire 5, the effect being to operate the line-lamp 13 in the usual manner. When the operator at the central station in response to this signal inserts her answering-plug 19, the line-lamp 13 is extinguished by the action of battery 50^a upon the cut-out relay 52, which is thereby energized to attract its armature and to open the circuit of battery 8 in the cus-

tomary manner. At the same time magnet 41 is energized and draws up its armature, thus completing the circuit of local battery 40 and lighting the lamp 42. This lamp remains lighted, and thus serves in its capacity of a supervisory signal while central is signaling to the other subscriber, because although one side of the repeating-coils 22 24 are energized from the common battery 23 the tension of spring 35 has been so adjusted that the core of said coil is of insufficient strength to draw up its armature 34. When the subscriber at the right lifts his receiver in response to a signal from central operator, he closes the circuit through the mercury in his instrument, thereby permitting current from battery 23 to flow through the other half of the repeating-coil and causing the armature of said coil to be raised by reason of the added effect of said coil. This action extinguishes the lamp 42 (thus notifying central that the subscriber called for has responded) by opening the circuit between 34 and 39. The parties are therefore in the conversational position shown in Fig. 1, and the lamp 42, which is now temporarily dark, enters upon its second function by serving as a "clearing-out" signal ready to light up once more when both subscribers have finished conversation. Should lamp 42 remain lighted after central signals the subscriber at the right, she proceeds to ring him up again by manipulating her ringing-key 27 until the lamp 42 is extinguished, which indicates that the subscriber has responded. She thereafter pays no further attention to the connection until the lamp should once more become lighted. After armature 34 has been drawn up by the repeating-coil, so as to extinguish lamp 42, said lamp will not again be lighted until both subscribers have placed down their receivers, for the reason that owing to the proximity of armature 34 to the core of the repeating-coil the current flowing in either half of the energizing-coils 22 24 alone will be sufficient to maintain it in its attracted position against the tension of spring 35. It will therefore be apparent that after the subscribers have been connected and are in conversation either one or the other may leave his instrument temporarily for the purpose of looking up any required information, &c., without operating the clearing-out lamp 42. If both subscribers, however, leave their instruments, the circuit from battery 23 will be broken at both ends, thereby deenergizing the core of the repeating-coil, allowing armature 34 to drop and causing lamp 42 to light, upon seeing which the central operator will pull out her connecting-plugs without further question or information, thereby extinguishing the lamp through the demagnetization of relay 41.

When the lamp or other signal 42 is to be used merely for clearing-out purposes, the

tension of the spring 35 is reduced sufficiently to permit its armature 34 to be drawn up the moment central inserts her plug in response to a call from a subscriber and remains in this condition until both subscribers after being connected have finished conversation and laid aside their instruments, whereupon the lamp is lighted and central immediately takes down the connection and clears the line. Should the subscriber called for fail to respond, the calling subscriber can again attract the attention of central by tilting his receiver, and thus causing the clearing-out lamp to flash.

The armature-operating coils may either be those of the repeating-coil itself, as just described with reference to Fig. 1, or they may be separate helices in circuit with said coils and wound upon a separate relay-core common to both, as shown at 45 in Fig. 2, in which latter case the magnetic circuit 22' of the repeating-coil is not broken and the type of repeating-coils at present in use on common-battery switchboards may be retained.

In Fig. 3 the lamp 13 is shown as in the direct line-circuit instead of being in a local circuit controlled by a relay 9, as in Fig. 1. In the case of the arrangement shown in Fig. 3 it is obvious that the return-signal given by 53 will show without question whether the signal is received or not at the central office, whereas in the case of the arrangement shown in Fig. 1 the failure of the lamp to light through defect of the local circuit or devices in said circuit would not be indicated on 53 at the subscriber's station.

The gravity-operated devices described are in their general manner of operation substantially the same as set forth in my prior application for patent filed June 23, 1899, Serial No. 721,521.

From what has been said it will be seen that the repeating-coil shown in Fig. 1 is employed by me not only in its capacity of an inductional transformer for the voice-currents, but also as an electromagnet for operating the lamp 42, which, as already stated, may serve either as a supervisory or clearing-out lamp, or both. The right and left hand coils may be wound around the core 22' either in the same or in opposite directions without affecting the operation of the device as a medium for the inductional transference of the voice-currents when the diaphragm of the transmitter at one or the other side is vibrated. In order, however, to prevent the entire or partial neutralization of the core 22' by the simultaneous closing of the battery 23 through both sets of coils 22 24, 22 24, I prefer to wind the coils upon the core in the same direction, so that their effect upon the core and its armature 34 will be cumulative. In this manner it will be seen that the magnetic circuit of the repeating-coil is not only closed while conversation is going on, but

also that when the armature 34 has once been drawn up by the combined action of both coils (where this arrangement is adopted) it will remain in this position, even if one or the other subscriber lays down his receiver, by virtue of the closing of the air-gap between the core 22' and the armature 34. If, however, the second subscriber also lays down his receiver or releases his hold upon it, the core 22' will be completely deenergized and release its armature 34, which coming in contact with the stop 39 completes the circuit of battery 40 and again lights the lamp 42, which thus becomes a positive clearing-out signal, upon seeing which the operator takes down the connection, as already described.

When my invention is applied to existing common-battery switchboards, in which repeating-coils of the closed-magnetic-circuit type are already provided, I prefer to employ the arrangement shown in Fig. 2, in which I use a separate relay 45, provided with two windings in series, respectively, with the helices of the repeating-coil. The action of relay 45 upon its armature 34 and lamp 42 will in other respects be precisely the same as that above described with respect to the construction shown in Fig. 1.

It will also be understood that my invention may be temporarily applied to existing switchboard equipments of the usual type, (in which the cord-circuits are provided with two supervisory lamps and with the usual pilot-lamp,) while the necessary changes in installation are being effected with great advantage to the service. In such cases when one of two connected subscribers lays down his receiver one of the two supervisory lamps lights up, as has heretofore been the case when the subscriber has restored his receiver to its hook-switch, which he frequently does when he temporarily leaves his position at the instrument. However, when my instruments take the place at the subscriber's station of the present type of hook-switch apparatus the central operator pays no attention whatever to the illumination of but one of the supervisory lamps, since such signal indicates merely that one of the two subscribers has left his instrument for the purpose of looking up some desired information for the other and that the other subscriber, whose supervisory lamp is dark, is holding the wire. Since by my invention the lamp-circuit is closed by the natural act of releasing the receiver, (instead of by hanging it upon a hook-switch or otherwise disposing of it in manner requiring it to be placed in some predetermined position by the voluntary act of the subscriber,) it follows that only when both of the present supervisory lamps remain steadily lighted is central required or justified in taking down a connection. By my invention therefore, whether applied to single or double supervisory-lamp switchboards, it

will be apparent that the signaling system is rendered positive, that central has at all times complete supervision over the condition of any two connected lines, that there can be no "element of doubt" as to the meaning of the subscriber's signals, as under existing practice, that central is not obliged after once having established connection to "listen in" or make inquiries in order to ascertain whether or not the line is still in use, as is so often necessary under the present system, that lines cannot be idly tied up or reported as being "busy" by failure on the part of the switchboard operator to properly interpret her supervisory or clearing-out signals, that connections are more rapidly obtained and when obtained not likely to be broken into by operators to the detriment of the subscribers, and, finally, that the work of central operators in establishing, supervising, and taking down connections is very much simplified and the service itself improved and greatly expedited.

I am aware that it has been before proposed to employ a supervisory signal the purpose of which is to leave the central-office operator nothing to do but to watch such signal; but in such system as heretofore organized it is still necessary and is, in fact, part of the operator's duty to listen in in case a certain length of time has elapsed without her getting the clearing-out signal with the purpose of seeing if conversation is finished. This it is necessary for her to do, because of the fact that hook-switches are employed in such previous systems, and it therefore frequently becomes necessary when no clearing-out signal is received and when by listening in it is ascertained that conversation is finished to cause a special buzz signal to be sent warning the subscriber, who may have carelessly left his instrument off the hook, to restore the same. In my improved system, however, the operator simply follows implicitly the indication of the supervisory or clearing-out lamp, since owing to the peculiar kind of telephone-switch employed by the subscriber she may know positively that so long as the lamp fails to light the line is in use for conversation and may likewise know that when it does light both subscribers have resigned the use of the line.

What I claim as my invention is—

1. In a telephone-exchange, the combination with a single lamp or signal device operating both as a supervisory and a clearing-out signal, of means for operating the same when the central-office operator inserts the answering-plug, and means responsive to a change in the electric condition of both of two connected subscribers' lines for throwing said signal out of operation during conversation, and into operation only when both subscribers resign the use of the line.

2. In a telephone-exchange, the combina-

tion with a clearing-out signal at the central office subject to the conjoint action of two connected subscribers' circuits, of subscribers' apparatus embodying automatic switching or circuit-changing devices of the gravity type, constituting a part of each receiving instrument, and means at the central office controlling said clearing-out signal and adapted to call the same into action only when the receivers of both of two connected subscribers are tilted from the position which they occupy when in use for listening.

3. In a telephone-exchange apparatus, the combination with two connected subscribers' circuits, of a coil in each, an armature acted upon by said coils conjointly, a signal-circuit controlled by said armature and a relay also controlling said circuit and connected to a contact upon the operator's plug adapted to close the circuit of said relay when the plug is inserted in the spring-jack in response to a call.

4. In a telephone-exchange apparatus, the combination with a repeating-coil, of an armature acted upon by parts of said repeating-coil which respectively are in the circuits of two connected subscribers, a supervisory or clearing-out signal responsive to the action of said armature when against its back contact, a second armature responsive to the action of a local circuit closed through a spring-jack, and a circuit for the signal including the front contact of the latter armature.

5. In a telephone-exchange apparatus, the combination with a supervisory or clearing-out signal, of means for controlling the same responsive to the conjoint change of electric condition in the circuits of both of two connected subscribers and subscribers' apparatus comprising automatic switching or circuit-changing devices of the gravity type embodied in or constituting a part of the receiving instrument itself, as and for the purpose described.

6. In a telephone-exchange apparatus, the combination of a repeating-coil, a supervisory or clearing-out signal, means for controlling the same responsive only when both parts of the repeating-coil act which respectively are in the circuits of the two connected subscribers and subscribers' apparatus comprising automatic switching or circuit-changing devices of the gravity type embodied in or constituting a part of the receiving instrument itself, as and for the purpose described.

7. In a telephone-exchange apparatus, the combination with a single supervisory signal device, of means for bringing the same into action when the operator plugs into the calling-line, and means for throwing the same out of action when the called subscriber responds and into action only when both subscribers resign the line, said means comprising an electromagnet at the central office

having coils in both subscribers' circuits, and subscribers' apparatus comprising automatic circuit-changing or switching devices of the gravity type, embodied in or constituting a part of the receiving instrument itself, as and for the purpose described.

8. In a telephone-exchange apparatus, the combination with a signal clearing-out device and actuating-coils connected respectively to the circuits of two subscribers, of an armature controlling said signal device and a retractor adjusted as described to prevent the armature from responding to the action of one coil only but to be retracted when the circuit through both coils is interrupted.

9. In a telephone-exchange apparatus, the combination with the subscriber's switch for changing circuits from normal condition to condition for conversation, of a telltale-signal at the subscriber's station and means for

momentarily closing the circuit thereof as the switch passes from one position to the other.

10. In a telephone-exchange, the combination with the subscriber's apparatus, of a telltale-signal at the subscriber's station, a source of energy at the central office, a subscriber's switch for changing the circuits from normal condition to condition for conversation, and contacts operated by said switch in changing from one position to the other and adapted to close the circuit of the telltale, as and for the purpose described.

Signed at New York, in the county of New York and State of New York, this 18th day of May, A. D. 1904.
